UNITED STATES PATENT OFFICE.

RALPH BAGGALY, OF PITTSBURG, PENNSYLVANIA.

CASTING-MACHINE.

SPECIFICATION forming part of Letters Patent No. 746,237, dated December 8, 1903.

Application filed February 12, 1903. Serial No. 143,009. (No model.)

To all whom it may concern:

Be it known that I, RALPH BAGGALY, of Pittsburgh, Allegheny county, State of Pennsylvania, have invented a new and useful 5 Casting-Machine, of which the following is a full, clear, and exact description, reference being had to the accompanying drawings, forming part of this specification, in which—

Figure 1 is a vertical section of my casting-machine. Fig. 2 is a plan view of the machine. Fig. 3 is a detail view showing the pig-ejecting mechanism, the mold being inverted. Fig. 4 is an end elevation of the machine, partly in section, the mechanism for 15 shaping the upper end of the pig being omitted. Figs. 5 to 32 show end views and elevations, partly in section, of pigs cast in my machine.

The operation of casting copper pigs as 20 heretofore conducted has been very wasteful, not only because the apparatus which has been employed causes the spilling of a considerable portion of the metal in pouring it into the molds, but also because the pigs are 25 cast with fins which, absorbing oxygen from the air, become very brittle and break off in handling and shipping, thus occasioning a very considerable loss.

The object of my invention is to provide 30 means whereby the present losses resulting from the shipment of copper, whether the same be in pigs, slabs, or bars, may be eliminated. To accomplish this result, I use, preferably, water-jacketed molds whose 35 molding-cavities are designed so that the fins resulting from the casting process are concentrated at one or two points. Fins when so concentrated may be readily and completely removed by machinery, so that in 40 shipping it is impossible for any portion of the pig, however small, to be broken loose, and thus lost.

In the accompanying drawings, 2 represents the frame of the machine, and 3 is the 45 mold. The mold is of greater height than width and has hollow walls 4 for the passage of a stream of water, and with trunnions 5 6, situate, preferably, about the middle of the mold, through which inlet and outlet pipes 7 50 and 8 extend for the introduction of water

to cool the mold. The arrangement of the water-passages in the mold is novel. The water enters a chamber 4' at one side of the mold, from the top of which it overflows through a passage 4^a into the main water- 55 passage 4 around the mold-cavity. Thence after filling the main cavity it flows through a passage 4^b at the top into a side chamber 4^c, from which it flows through the outlet-pipe 8. As the mold is filling the air rises to the top of 60 the chambers 4, 4', and 4^c and is displaced through the passages 4^a and 4^b and is caused to go out through the pipe 8. To rotate the mold on its trunnions, I prefer to employ a pinion 9, which is fixed to one of the trunnions and is operated by a rack 10, fixed to 65 and movable with a cylinder 11, which is reciprocated on a plunger 12, the latter being hollow and serving for the introduction and discharge of the water or compressed air by 70 which the cylinder is operated. At the base of the mold is a movable plug or end piece 13, which is adapted to be moved inwardly when the mold is rotated into inverted position by means of an eccentric groove 14, 75 which engages with rollers 15 on the plug. The inner end of the plug is preferably shaped as at 16, so as to form a rosette or plain portion at the end of the pig, and the shape of the plug is such as to form a pig 80 with a concave end, although, if desired, it may be shaped so as to form a pig with a projection at the end, the purpose in either case being to afford means by which the pig may readily be seized and handled. The upper 85 end of the mold has at the side of the mold-cavity a trough or basin 17 for receiving any surplus metal which may remain in the pouring-ladle after the mold has been filled, and extending above this basin there are preferably stop-arms 18, the purpose of which I 90 describe below.

Above the mold is a vertically-movable end piece or plug 19, which is shaped like the end piece 13 and is vertically movable by a 95 plunger 20, operated by a cylinder 21, the motive power of which may be compressed air or water. The plug 19 is preferably attached removably to the plunger 20 by a key 22, so that it may be replaced when de- 100

sired, and the plugs 13 and 19 are water-cooled by flexible inlet and outlet pipes 19'.

23 is an arm pivoted to a bracket 24 and extending down into the basin 17, having at its 5 lower end a projection or tongue 23'.

25 25 are wheels journaled in the uprights of the machine-frame and adapted to constitute rests for the trunnions of the ladle, and 25' is a spout which conducts the metal to 10 the cavity of the mold 3.

The parts being in the position shown in Fig. 1, except that the upper plug 19 is retracted above the mold, and the mold being water-cooled by passage of water through 15 its hollow walls 4, molten metal is charged into the ladle 25" from a furnace or converter, in proximity to which the casting-machine is set, and the ladle is tilted on the wheels 25, so as to discharge the molten copper into the 20 mold. The ladle has a capacity just a little in excess of the capacity of the mold. When the copper has risen in the mold to the desired height, which may be indicated by a mark in the mold-cavity, the ladle is righted 25 and is moved on the wheels so as to bring its pouring-spout over the basin 17, and any surplus metal which may remain in it is then poured into the basin, from which it is afterward removed, as explained below. When 30 the mold has been filled, the plunger 20 is brought down, and the plug 19 enters the still molten copper in the interior of the pig and shapes the end of the pig, which rapidly sets, because of the cooling of the 35 mold and plunger by water. The down pressure on the plunger 20 need be sufficient only to shape the end of the pig and is not sufficient to exert undue strain upon the machine or the setting metal of the pig. The 40 plug 19 is then retracted and the mold rotated on its axis into the inverted position shown in Fig. 3, and during such rotation the guiding-groove 14 causes the bottom plug 13 to advance and to loosen the ingot, which 45 then drops from the end of the mold, the mold-cavity being flaring in shape to facilitate the discharge. The same motion of inverting the mold causes the arm 23, which is upheld by the bracket 24, to loosen the 50 surface piece of copper in the basin 17, because the piece of copper is temporarily upheld by the arm 23 until it is loosened from the basin by the rotary motion of the mold. If this piece of copper should stick to the arm 23, it 55 is disengaged therefrom when it strikes the arms 18, and when the mold is inverted the loosened piece of copper drops freely from the basin. It is then thrown into the mold and incorporated in the next pig in order 60 that no waste shall occur. After the discharge of the pig the mold is immediately righted, and another pig can then be cast. The operation is thus very rapid and can be carried on with the labor of only one man.

65 By reason of the shape of the ends of the plugs 13 and 19, as indicated at 16, project-

ing rosettes 26 are formed at the bases of the concave portions 27 at the ends of the ingot 28, and on one of these rosettes the weight of the ingot may be stamped. On the other one 70 the name of the person for whom the ingot is made may be cast.

If desired, the end plug 19 may not be used, in which case the upper end of the pig will not be shaped as described above and the 75 side supplemental mold or basin will not be used.

In the figures on the fourth sheet of the drawings I show pigs which are cast in my mold. Their design is such that they are shapely and 80 easily handled and the weight and name marks are protected from injury. By reason of being cast in a water-cooled mold, in which they chill quickly, they are smooth and uniform in appearance, and if they are immediately discharged into water from the molds while still hot the coating of black oxide will be removed and they will present a bright appearance. All the fins are purposely concentrated by the design of the pig for ready 85 and complete removal by suitable trimming machinery, and such fins are then returned to the mold and become incorporated in the next pig that is cast, thus preventing every 90 item of the waste that now prevails. 95

In another application, Serial No. 147,984, filed March 14, 1903, I claim a pig-casting machine having a mold normally in upright position and adapted to be rotated, said mold having at its end a movable plug and means 100 for projecting the plug during the rotation of the mold.

Within the scope of my invention the apparatus may be modified in various ways, 105

What I claim, and desire to secure by Letters Patent, is—

1. A copper-pig-casting machine having a normally upright mold of greater height than width, pivotally mounted near the middle of 110 its height, and having water-cooled hollow walls, said mold being adapted to be inverted to discharge the pig, and having means by which it is inverted; substantially as described. 115

2. A pig-casting machine having a normally upright water-cooled mold, with water-cooled plugs adapted to shape the ends of the pig; substantially as described.

3. A water-cooled mold having its upper 120 end open to receive molten metal, and having at the side of the open upper end a basin for surplus metal, and a metal-lifting device in the basin for removing the solidified metal therefrom; substantially as described. 125

4. A copper-pig-casting machine having an oblong water-jacketed mold, and a tapering plug at the end of the mold adapted to form a pig with a concave end constituting a hand-hold; substantially as described. 130

5. A copper-pig-casting machine having an oblong water-jacketed mold, and a tapering

- plug at the end of the mold adapted to form a pig with a concave end constituting a hand-hold, said plug being movable and water-cooled; substantially as described.
- 5 6. A pig-casting machine having a mold and a piston having a water-cooled plug adapted to enter the upper end of the mold to shape the upper end of the pig; substantially as described.
- 10 7. A water-cooled mold having at its upper end a basin for the reception of surplus metal, said mold being adapted to be rotated to discharge the pig, and means for disengaging the metal in the basin when the mold is rotated; substantially as described.
- 15 8. A rotatable mold having a water-jacket-

ing chamber 4 and side passages 4', 4° connected with the chamber 4 by passages at the top; substantially as described.

9. A rotatable mold having a water-jacketing chamber 4 and side passages 4', 4°, connected with the chamber 4 by passages at the top, said mold having trunnions and water-passages extending therethrough into the side passages; substantially as described. 25

In testimony whereof I have hereunto set my hand.

RALPH BAGGLEY.
